2 Sheets-Sheet 1

A technical line drawing of a mechanical assembly, possibly a press or stamping machine. The drawing shows a central frame with various mechanical components. Key features include a large circular component labeled 68, a lever system with labels 45, 41, 46, 47, 54, 55, 50, 51, 80, 81, 70, 68, 71, 71, 60, 62, 63, 36, and 37. The drawing is labeled 'Fig. 2.' at the top center.

TYPEWRITING MACHINE

Application filed June 7, 1928, Serial No. 283,539, and in Belgium March 15, 1928.

My invention relates to a machine for composing typographical text, operating upon the principle of typewriting machines, that is to say a machine in which the typographical composition to be reproduced is obtained by manipulating keys actuating type bars co-operating with a carriage carrying a sheet on which the text is to be typed and if desired provided with suitable inking devices.

10 It is well known that any typewriting machine of whatever description it may be can be employed for preparing a plate intended for reproduction. Such a printing plate however presents the feature that it does not 15 provide a so-called typographical composition, that is to say a composition in which the characters give an exact reproduction of text composed by means of typographical characters having bodies of different thicknesses (widths) according to the size of the letters to be employed. This disadvantage, which has up to the present time prevented the adoption of typewriting machines for 20 composing text to be printed, results from the fact that in most typewriting machines the characters have bodies of a uniform thickness (width) so that the spaces corresponding to these characters are all exactly 25 the same.

30 The object of my present invention is to remove this disadvantage and consequently to provide improved means for obtaining a varying spacing proportional to the thickness of each character so that the type bars 35 can be provided with characters corresponding absolutely to the actual typographical characters.

With this object in view, my invention essentially consists in the special arrangements 40 and combinations of parts hereinafter fully described and pointed out in the appended claims.

On the annexed drawings:

Figure 1 shows diagrammatically in elevation and in section a general arrangement

of the control mechanism of a type bar and the spacing mechanism.

Figure 2 is an elevation of the back part of the machine showing the device for controlling the spacing movement.

50 Figure 3 is a plan view of a part, corresponding to a section taken along the line III-III in Figure 1 so as to show in plan the spacing bars and the selecting slot co-operating with these spacing bars.

55 Figure 4 is a plan view of the type carrying members.

Figure 5 is a vertical section to a larger scale of a part of the control mechanism of the movement of escapement shown in Figure 1.

60 Figure 6 is a side elevation corresponding to Figure 5.

The machine chosen for illustration is of a common and well known type and comprises 65 a frame 1, provided with ball bearing channel bars 2 upon which are adapted to slide the front and rear rails 3 of the carriage frame, which frame is provided at each end thereof with a pair of upwardly extending arms 4, 70 as shown in full lines in Fig. 2, and in dotted lines in Fig. 1, each pair of arms forming between them a slot 4^a for guiding the carriage in its vertical movements. The carriage is designated generally by 5 and includes a typestriking surface 6 in the form 75

of a platen. The carriage carries suitable bearings in which is mounted the main feed roller 7, around which is fed a sheet 7^a of paper, rubber or other suitable material which is to receive the imprint of the type. The sheet 7^a, after passing below the roller 7 is guided between a pair of rollers 8 toward the platen 6, and after passing in front of the latter is fed between a pair of rollers 8^a, one of which is driven by surface contact with a roller 8^b, which in turn is driven by surface contact with the main feed roller 7. The carriage also carries the usual sheet metal apron 8^c on which the sheet 7^a rests and by 85 90

which it is directed into engagement with the roller 7. It will be understood that the bearings for all of the rollers above referred to are carried by the frame of the usual movable carriage common in typewriters, and since this portion of the machine forms no part of the invention the carriage frame has been omitted from the drawings.

The type characters 9 are carried by type bars 10 pivoted at 11 in a segment 12 which is provided with supports 13 having open-ended slots for connection as indicated at 14 with a supporting bracket 15, as shown in Fig. 4, said bracket being integral with the frame 1 of the typewriter. When the keys are struck the type bars are guided as in all typewriting machines by means of a guide 16 (Figs. 1 and 4) placed in front of the platen 6. Each type bar is subjected at its end to the action of a lever 17 upon which acts a rod 18 connected to a bent lever 19 pivoted at 20 upon a support 21. The lever 19 is itself connected by a rod 22 to the control bar 23 carrying the key 24. Each control bar 23 is pivoted at 25 upon a cross member 26 and is acted upon by a return spring 27. In practice each type bar 10 is provided at 9 with a certain number of different characters, for example capital letters, small letters, italics, figures, etc. As usual, one character or another is caused to strike as desired by giving the carriage 5 a lifting or lowering movement in the slots 4 of the carriage support by means of any mechanism, a part of which is shown in Figure 1 which comprises a vertical rod 28 passing through a guide 29 and given a lifting and lowering movement by a fork 30 keyed upon a pivot 31 operated from the outside of the machine by a suitable lever. In the example shown, the rod 28 acts through the medium of a plate 32 upon a stop 33 carried by a movable carriage 5, so that this carriage can take up any desired position in height according to the particular character on the plate 9 which must be made to strike the printing plate passing in front of the platen 6. As these characters are typographical characters as employed in printing, they have different thicknesses (widths). In order to make the movement of advance of the carriage, that is to say the spacing, corresponding in each case to the character struck, it is necessary to give the carriage 5 a varying movement of escapement. Moreover the spacing must vary for each type bar according to the character which is carried by the bar, since the space corresponding to the letter M for example, must be greater than the space corresponding to the space I and so on for each character considered.

For each of the types of characters (capital letters and small letters, for example) carried by the bar 10 there corresponds a spacing bar and, in the case of different characters

carried by each type bar, as is shown, use is made of two similar spacing bars 34 and 35 oscillating upon two pivots 36-37 extending longitudinally at the back of the machine.

Each control bar 23 for a type bar 10 is 70 provided at its end with a strengthening plate 38 which, when the end of the control bar is lifted, acts upon the corresponding spacing bar 34 or 35 through the medium of a stop 39. For each control bar 23 there corresponds, as a consequence, upon each spacing bar, a similar stop 39 the height of which varies from one letter to another so as to communicate, for a given movement of oscillation of the control bar 23, a different amplitude of oscillation, to the spacing bar 34 or 35 considered.

Above these spacing bars is disposed a movable slider 40 keyed upon a shaft 41 (Figure 3) carried in a forked shaft support 42 secured upon the plate 43 extending transversely in the central back part of the machine. The slider 40 normally rests, under the action of its weight, by means of a stop 44 with which it is provided, upon one of the spacing bars 34 or 35 in the central part of the latter. Upon the end of the shaft 41 is keyed a lever 45 pressing normally against a projection 46 carried by a side plate 47 forming a part of the escapement controlling mechanism. This mechanism comprises a second similar side plate 48 (Figure 5). The two side plates 47-48 are mounted by ball bearings 49 upon a spindle end 50 upon which is keyed between the side plates a circular plate 51 against which presses normally a lever 52 provided with an eccentric shoe 53. This lever 52 pivots upon a rod 54 supported by the side plates 47 and 48 and is acted upon by a spring 55 (Figures 2 and 6) which keeps the shoe 53 pressed against the periphery of the plate 51. Further, upon the shaft 50 (Figure 5) is mounted a plate 56 provided with a friction surface 57 against which presses a plate 58 adapted to move longitudinally upon a sleeve 59 integral with a drum or a plate 60 turning freely upon the shaft 50 and provided at its periphery with a helical groove 61 in which passes a cable 62 (Figure 2) making a complete turn round the drum 60 and the ends of which are connected at 63 to lugs depending from one of the movable carriage rails 3.

The plate 58 which is adapted to slide upon the sleeve 59, is acted upon by a spring 64 (Figure 5) which keeps it pressed against the friction surface 57 of the plate 56 and is adapted to be displaced axially upon the sleeve 59 by means of a forked lever 65 (Figure 1) pivoted at 66, which is controlled by a lever 67 mounted upon a shaft 68 adapted to be made to oscillate from the outside of the machine by a suitable handle. Further, the plate 32 controlling the lifting and lowering movement of the carriage 5 is provided 130

with a plate 69 comprising projections 70 which can act, when the upward and downward movement of the rod 28 takes place upon a rod 71 displaceable horizontally, 5 which by its other end acts upon a lever 72 oscillating at 73 and exerting, through a roller 74 a pressure upon the arm 75 of the slider 40 which is held pressed against the roller 74 by a return spring 76.

10 The mechanism described operates in the following manner:

If we assume a sheet, intended to serve as a printing page, to be placed in the carriage 5 and passing in front of the plate 6 when one 15 of the keys 24 is lowered, the corresponding control lever 23 produces, through the medium of the rod 22, the lever 19 and the rod 18, the pivotal movement of the type bar so as to bring the type carried at 9 against the 20 platen 6, the type bar becoming situated, at this moment, in the guide 16.

At the same time, if we assume the carriage to be in its highest position, the control bar 23, by becoming raised at its back 25 end, encounters the stop 39 which corresponds to it and makes the spacing bar 34 pivot upon the shaft 36. As at this moment, as a result of the position in height of the carriage, the stop 44 with which the slider 40 is provided, 30 rests upon the first spacing bar 34, the latter in rising makes this slider 40 pivot with the shaft 41 in the support 42 and the lever 45 pushes against the stop 46 carried by a side plate 47.

35 As a result of this the lever 52, provided with a shoe 53, pivots about the shaft 50 without taking with it the plate 51, the shoe 53, as a result of its eccentricity, moving freely upon the periphery of the plate 51. But as 40 the side plate 47 is connected by a cable 77 (Figure 2) to a spring drum 78, this movement of the side plates 47 and 48 has the effect of putting the spring 78 under tension so that at the moment when the blow is struck 45 and the key 24 is released, this spring drum 78 exerts a pull upon the side plates 47 and 48 in such a way that the shoe 53 carrying along the plate 51 makes the shaft 52 turn, which drives through the plate 56 and the 50 friction 57, the plate 58, which makes the grooved pulley 60 turn, over which passes the cable 62.

The latter thus displaces the carriage by the desired amount corresponding to the desired spacing. If on the other hand, the carriage 5 is lowered by acting upon the shaft 31 by means of its control rod in order to strike another type of character carried by the type bar 10, this movement of displacement 55 has the effect of acting, by the cam 70, upon the rod 71, which, by becoming engaged in the hollow of the cam, permits a displacement of the slider 40 in the direction of the arrow 70 so as to bring the stop 44 above the 60 second spacing bar 35.

As this bar is provided, on its side with a series of stops 39 corresponding to the required spacing, the strengthening plate 38 when the key 24 is lowered, acts upon the second spacing bar 35 which in its turn makes 70 the slider 40 pivot, which operates in the same manner as before the movement of control of the spacing but by a different amount, the amplitude of oscillation of the slider being modified by the difference in length of the 75 stop 39 carried by the second spacing bar 35.

If it is desired to move the carriage backwards, it is sufficient to act, by the control lever connected to the shaft 68, upon the lever 67 which, through the medium of the 80 lever 65, disengages the friction plate 56 from the plate 58, so that at this moment the carriage can be moved without taking with it the plate 56 and consequently independently from the spacing movement. 85

The spacing bars 34 and 35 naturally are each provided with as many stops 39 as there are control bars 23 and consequently type bars 10 in the machine, and each of these stops comprises a projection corresponding 90 to the spacing movement necessitated by the thickness (width) of the typographical character carried by the type bar 10. In the case when the type bar carries a number of types of characters or signs which is greater 95 than two, the number of spacing bars corresponds to this number of characters and the lifting and lowering movement of the carriage is provided with a cam 70 adapted to make the lever 72 occupy, through the 100 medium of the rod 71, different positions bringing in succession the slider 40 and its stops 44 above the corresponding spacing bar.

The machine is obviously provided with 105 all accessories permitting its normal use. It may be provided with inking devices if it is intended to employ it as a simple typewriting machine or as a machine for composing text to be reproduced by lithographic printing. 110 The printing plate may also be constructed in such a way as to permit its direct use of ordinary typographical printing.

In view of the variation in spacing according to the thickness (width) of the typographical characters carried by the type bars 10, the text reproduced is always identical with the lithographic text composed by means of ordinary typographical characters. 115

In practice the backward rotation of the 120 plate 61 is prevented by a second eccentric shoe 80 held pressed against this plate by a bar 81 forming a counter weight so as to prevent any movement of the carriage when the side plates 47 and 48 oscillate at the 125 moment the spacing mechanism becomes cocked for producing a space. If it is a question of producing typographical printing plates the characters may be engraved backwards and the movement of the carriage 130

may be the reverse of that corresponding to the ordinary direction of writing.

What I claim is:

1. In a typewriting machine, in combination, a frame, a carriage adapted to receive a printing plate and sliding on the said frame, a striking surface provided on the said carriage, type bars, sets of typographical characters of varying thickness carried by said type bars, means whereby the said striking surface is adapted to be struck by the said types, means whereby the type bars are guided when struck against the striking surface, means whereby a lifting and lowering movement is given to the said carriage to bring the carriage into position for using a respective set of characters, a control key for each of the type bars, spacing bars for each set of characters and on which act the said control keys, stops of different heights, provided on the said spacing bars, whereby for one lowering of the key controlling the type bar, the spacing bar receives a movement of amplitude proportional to this stop, an escapement movement including a friction clutch whereby the movement of the spacing bar is transmitted to the carriage, a slider adapted to be interposed between the spacing bar corresponding to the type of character to be struck and the escapement movement, and adapted to be displaced automatically by the lifting and lowering movement of the carriage, whereby the selection of the spacing bar corresponding to the type of character to be struck is effected.

2. In a typewriting machine, in combination, a frame, a carriage adapted to receive a printing plate and to slide on the said frame, a striking surface provided on the said carriage, type bars on which sets of typographical characters of varying thickness are mounted, means whereby the said striking surface is adapted to be struck by the said types, means whereby the type bars are guided when struck against the striking surface, means whereby a lifting or lowering movement is given to the said carriage to bring the carriage into position for using a respective set of characters, a control key for each of the type bars, spacing bars for each set of characters and on which act the said control keys, a shaft, an escapement movement, a slider mounted on the said shaft and adapted to be interposed between the spacing bar corresponding to the type of character to be struck and the escapement movement, and adapted to be displaced automatically by the lifting and lowering movement of the carriage, whereby the selection of the spacing bar corresponding to the type of character to be struck is effected, means whereby a movement of oscillation is given to the said selecting slider from the spacing bar, a lever keyed on the end of the said shaft, a wheel, a cable, connected to the said wheel and to the car-

riage, a second wheel made rigid with the said first wheel, means whereby an angular rotation of an amplitude corresponding to the movement of oscillation of the selecting slider is given to the said wheels and whereby the movement of the spacing bar is transmitted to the carriage.

3. In a typewriting machine, in combination, a frame, a carriage adapted to receive a printing plate and to slide on the said frame, a striking surface provided on the said carriage, means whereby the material serving for the formation of the printing plate is guided, type bars, sets of typographical characters of varying thickness mounted on the said type bars, means whereby the said striking surface is adapted to be struck by the said types, means whereby a lifting and lowering movement is given to the said carriage to bring the carriage into position for using a respective set of characters, a control key for each of the type bars, spacing bars for each type of characters, and on which act the said control keys, a shaft, a slider mounted on said shaft and adapted to be movable by the spacing bar corresponding to the type of character to be struck and adapted to be displaced automatically by the lifting and lowering movement of the carriage whereby the selection of the spacing bar corresponding to the type of character to be struck is effected, means whereby a movement of oscillation is given to the said selecting slider from the spacing bar, a lever keyed on the end of the said shaft, a second shaft, a friction plate on the said second shaft, two side plates adapted to pivot about the said second shaft, an eccentric shoe carried by the said side plates and adapted to engage and rotate said friction plate when said shoe is driven in one direction by the said side plates, a spring drum whereby the said side plates are acted upon and whereby the movement of the carriage is produced at the moment the key serving for striking the character is released.

4. In a typewriting machine, in combination, a frame, a carriage adapted to support a printing plate and to slide on the said frame, means whereby the material serving for the formation of the printing plate is guided, type bars, sets of typographical characters of varying thickness mounted on the said type bars, means whereby the said striking surface is adapted to be struck by the said types, means whereby the type bars are guided when struck against the striking surface, a vertical rod, a lever acting on the said rod, whereby a lifting and lowering movement is given to the said rod and also to the carriage to bring the carriage into position for using a respective set of characters, a cam on which acts the said rod, a horizontal rod, a lever adapted to be oscillated, a slider, means whereby the said lever is adapted to act on the

said slider, spacing bars in a number corresponding to the number of sets of characters to be struck, means whereby the said slider is adapted to be movable by the spacing bar corresponding to the set of characters to be struck, a control key for each of the type bars, the keys acting on the said type bar and means including a friction clutch whereby the movement of the spacing bars is adapted to be transmitted to the carriage.

In testimony whereof I have affixed my signature.

ALEXANDRE HAVARD.
